MULTI-TANK AQUARIUM

Milton R. Cohen, 200 E. 71st St.,
New York, N.Y. 10021

Filed Feb. 24, 1970, Ser. No. 21,593

Term of patent 7 years

Int. Cl. D30—01

U.S. Cl. D30—6

FIG. 1

FIG. 3

FIG. 2

FIG. 5

FIG. 4

FIG. 1 is a front perspective view of a multi-tank aquarium showing my new design;

FIG. 2 is a side elevational view;

FIG. 3 is a rear elevational view;

FIG. 4 is a view similar to FIG. 2 but showing a modified form of my new design wherein the cover components have been turned 180 degrees and interchanged on the two tanks; and

FIG. 5 is a view similar to FIG. 2 but showing another modified form of my new design wherein the cover of the bottom tank has been replaced by a cover like the one on the top tank but in a reverse position from the top tank cover.

The ornamental design for a multi-tank aquarium as shown and described.

I claim:

The ornamental design for a multi-tank aquarium, as shown and described.
